ATTY.

UNITED STATES PATENT OFFICE.

SAMUEL KELSO, OF TORONTO, ONTARIO, CANADA.

DESIGN FOR A SWIMMING-BELT.

56,815.

Specification for Design.

Patented Dec. 28, 1920.

Application filed June 26, 1920. Serial No. 392,107. Term of patent 7 years.

To all whom it may concern:

Be it known that I, SAMUEL KELSO, a subject of the King of Great Britain, residing at the city of Toronto, in the county of York, Province of Ontario, Canada, have invented a new, original, and ornamental Design for Swimming-Belts, of which the following is a specification, reference being had to the accompanying drawing, forming part thereof.

Fig. 2 a front view of the same.

I claim:

The ornamental design for a swimming belt, as shown.

SAMUEL KELSO.
